UNITED STATES PATENT OFFICE.

CHARLES H. KIRBY, OF DETROIT, MICHIGAN.

METHOD OF MAKING PISTONS.

Application filed May 21, 1923. Serial No. 640,565.

To all whom it may concern:

Be it known that I, CHARLES H. KIRBY, a citizen of the United States of America, residing at Detroit, in the county of Wayne and State of Michigan, have invented certain new and useful Improvements in Methods of Making Pistons, of which the following is a specification, reference being had therein to the accompanying drawings.

10 This invention relates to pistons of the type in which the skirt is longitudinally slotted to produce lightness and internally ribbed to secure the necessary strength. Such pistons have proved very satisfactory 15 under operating conditions but the cost of manufacture has been higher than with the continuous skirt type because of the difficulty in machining. This is due primarily to the lack of rigidity in the skirt portion 20 of the piston casting because of the thin section of the metal and the interrupted peripheral surface.

To overcome this machining difficulty I have formed the casting with an integral ring forming an extension of the skirt, thereby increasing the rigidity and providing a continuous annular surface which can be readily supported in a lathe. The casting is then completely machined and in the 30 last operation the ring is removed leaving the finished piston with the divided skirt.

In the drawings:—

Figure 1 is a longitudinal section of a finished piston;

35 Figure 2 is a bottom plan view thereof;

Figure 3 is a sectional elevation of the piston casting;

Figure 4 is a sectional elevation at right angles thereto;

40 Figure 5 is a plan view of a double piston casting.

Figures 1 and 2 show a piston having the head A and the divided skirt portions B and B'. The piston is provided with bosses 45 C extending transversely of the divided skirt portion and the structure is strengthened by means of the internal ribs D.

Figures 3 and 4 represent the cast blank from which the piston above described may 50 be machined. This blank may be cast in the usual manner with the longitudinal slots E, thereby forming the diametrically opposite segmental portions F, but in order to secure rigidity in the casting, I have pro-

vided the integral ring G, the outer periphery of which is preferably of the same diameter as the head portion H. By means of the ring G the casting may be supported in the machine at either end and all of the operations for finishing the piston within the desired degree of tolerance may be performed while the segmental portions are rigidly supported. After the machining has been completed the piston may be supported at the head and the ring G removed thereby forming the piston shown in Figures 1 and 2.

Figure 5 represents a modified piston blank in which a single casting may be machined to form two finished pistons. In this view the blank I consists of the opposite end portions J and J' forming the heads of the pistons, the inwardly extending segmental portions K and K' and the central ring L integral with the segmental portions. It will be noted that the blank I may be 70 considered as being made of a pair of blanks, such as shown in Figures 3 and 4, having a common connecting ring. M and M' refer to the slots between the segmental portions K and K' respectively and it is due to these 75 slots that it is possible to cast the double piston blank, as shown, because it is necessary to provide a support for the dry sand cores while pouring the metal in the mold.

The blank I is preferably provided at its 80 opposite ends with axially aligned bosses T and T' in order that the blank may be supported upon centers U and U' during the machining operations. The centers preferably extend into the head portions J and J' 90 of the blank through drilled holes W and W' and the centers are reduced at X and X' to provide a clearance so that the bosses T and T' may be removed after the blank is 95 machined. The final operation of the machine is to separate the blank into the two pistons by removing the ring L.

The addition of the ring integrally formed with the segmental portions in both the single piston blank and the double blank 100 provides a rigid casting which simplifies the setting up of the blank in the machines. After all of the operations have been completed to provide a finished piston, the ring may be removed to leave the flexible segments B and B', as shown in Figures 1 and 2.

What I claim as my invention is:—

1. The method of fabricating pistons which consists in forming a casting having a head, segments extending therefrom, and an annular portion at the opposite ends of said segments, machining said casting while said annular portion is integral therewith to maintain a rigid structure and subsequently removing said annular portion to obtain a piston having flexible segmental portions. 5
10. 2. The method of fabricating pistons which consists in forming a cast blank for a plurality of pistons having a pair of heads at opposite ends thereof, segmental portions extending inwardly from said heads and a common annular portion connecting said segments, machining said blank while said annular portion is integral therewith to maintain rigidity in the structure and subsequently removing said annular portion to obtain a pair of pistons having flexible segmental portions. 15
15. 3. A piston blank comprising a head, segmental portions projecting therefrom and an annular portion at the opposite ends of said segments. 20
20. 4. A piston blank comprising a head, a pair of segmental portions projecting therefrom upon diametrically opposite sides of said blank, and an integral ring at the opposite ends of said segments, said ring forming a brace for said segmental portions to maintain rigidity during the machining of said blank and being adapted for removal subsequent to the machining operations to render said segments flexible. 25
25. 5. A cast blank for a plurality of pistons comprising a pair of heads at opposite ends thereof, segmental portions extending longitudinally inward from said heads, and an annular portion connecting said segments intermediate said heads. 30
30. 6. A piston blank comprising a hollow cylindrical casting closed at its opposite ends and having longitudinal slots in the sides, said blank being provided with a pair of integral bosses adjacent each of the opposite ends, and extending inwardly from the side walls, said blank also being provided with strengthening ribs in the interior thereof. 35
35. 7. A piston blank comprising a hollow cylindrical casting closed at its opposite ends and provided with a continuous annular portion midway between its ends, the sides of said cylindrical blank being formed with longitudinally extending slots between said annular portion and said closed ends, the inner surface of said hollow casting being provided with strengthening ribs and having inwardly extending bosses on opposite sides of said annular portion. 40
40. 8. A piston blank comprising a hollow cylindrical casting closed at its opposite ends and fashioned in the hollow interior to provide inwardly extending bosses and reinforcing ribs, said blank being formed with a continuous annular portion midway between its ends and having slots in the sides between said annular portion and said closed ends and axially arranged bosses projecting outwardly from the opposite ends of the blank. 45
45. 9. The method of fabricating pistons which consists in first casting a hollow cylindrical blank closed at the opposite ends and having slots in the cylindrical sides, machining the exterior of said blank and severing the blank in the middle to obtain two separate cup shaped pistons. 50
50. 10. The method of fabricating pistons which consists in first casting a hollow cylindrical blank closed at its opposite ends and provided with a continuous annular portion midway between the ends, the blank being formed with slots in its cylindrical sides between said annular portion and said closed ends, machining the exterior of said blank and subsequently removing the continuous annular portion to form two separate cup shaped pistons having flexible segmental portions. 55
55. 11. The method of fabricating pistons which consists in first casting a hollow cylindrical blank closed at its opposite ends having a continuous annular portion midway between the ends and slots between said annular portion and said ends, said blank being cast with axially aligned bosses projecting outwardly from the opposite ends, rotating said blank about its longitudinal axis, machining the exterior of said blank during said rotation, removing the bosses and finally removing the annular portion to obtain two separate cup shaped pistons, each having flexible segmental portions. 60
60. 12. The method of fabricating pistons which consists in forming a casting having a head, segments extending therefrom and an annular portion at the opposite ends of said segments, machining said casting while said annular portion is integral therewith to maintain a rigid structure and subsequently removing the annular portion adjacent to the segments to obtain a piston having flexible segmental portions. 65
65. 13. The method of fabricating pistons which consists in forming a blank having a head, segmental portions extending therefrom and a member connecting the other ends of said segmental portions for maintaining the latter in rigid relation to each other, machining said blank while said member is integral with said segments to maintain a rigid structure and subsequently severing said connecting member from the blank adjacent said segmental portions and removing said member to obtain a piston having flexible segmental portions. 70
70. 14. The method of fabricating pistons which consists in forming a blank for a plurality of pistons having a pair of heads at opposite ends thereof, segmental portions

extending inwardly from each of said heads and a member spaced from said heads and connecting said segmental portions to maintain the latter in rigid relation to each other, 5 machining said blank while said connecting member is integral therewith to maintain a rigid structure and subsequently dividing

said blank into two portions and removing said connecting member adjacent said segmental portions to obtain two separate pistons having flexible segmental portions. 10

In testimony whereof I affix my signature.

CHARLES H. KIRBY.
